UNITED STATES PATENT OFFICE.

HERBERT E. CUNNINGHAM, OF LOS ANGELES, CALIFORNIA.

RECTAL SUPPORTER.

No. 878,191.

Specification of Letters Patent.

Patented Feb. 4, 1908.

Application filed October 9, 1905. Serial No. 281,889.

To all whom it may concern:

Be it known that I, HERBERT E. CUNNINGHAM, a citizen of the United States, residing at Los Angeles, in the county of Los Angeles and State of California, have invented a new and useful Rectal Supporter, of which the following is a specification.

The objects of my invention are to provide a superior rectal supporter for the relief and 10 cure of fissure, hemorrhoids, and other rectal diseases; to provide a rectal supporter that will be self-retaining, and will exert pressure in the most advantageous manner on the parts affected; to provide superior means to 15 apply to the hemorrhoidal or other diseased rectal surface an unyielding contacting surface of fine texture and antiseptic qualities, and that will also have in itself a curative nature; to provide superior means for returning 20 and retaining any portions of the rectal lining that may be ordinarily subject to protrusion; to produce automatic massaging of the affected parts by action of the body of the wearer.

I may provide suspensory means to guard 25 against accidental displacement, but in general, the supporter embodying my invention will be held in place by the action of the rectal muscles alone. I also provide for superior electrical simulation or treatment of the part 30 affected.

The invention relates to the construction of the entire device and its members.

It also includes a rectal supporter made of zinc. I have discovered that a rectal supporter made of metallic zinc will by its corrosive qualities, promptly reduce inflammation in the affected parts; at the same time providing an appliance affording means whereby movement of the body of the wearer will 40 cause beneficial massaging of the parts. In this connection the supporter has a smooth exterior, and is approximately circular in cross-section, being of such a shape as not to form corrugations or folds in the lining of the 45 rectum.

In carrying out my invention in its most approved form, the supporter is made of an integral piece of zinc constituting an inner closure and an outer closure, and a thin or 50 narrow neck connecting said closures; and preferably, the entire appliance is perforated axially, and the several members thereof are arranged around a straight perforation.

The support may be variously constructed 55 for use in various forms of rectal disease. I shall illustrate and describe three of such

forms, although I do not limit myself to the exact construction shown in any of the forms I shall illustrate.

The accompanying drawings illustrate the 60 invention: Figure 1 is an elevation of the supporter with adjacent portions of the suspensory and circuit connection means. Fig. 2 is a vertical section of the supporter. Fig. 3 is an inverted plan of same. Figs. 4 and 65 5 show in elevation and axial section the form best adapted to treatment of the most common forms of rectal diseases. Fig. 6 is a sectional plan on line x^6-x^6 , Figs. 4 and 5. Figs. 7 and 8 show in side elevation and axial 70 section, an extreme form especially adapted to cases where the hemorrhoid lies directly over the sphincter recti. Fig. 9 is a bottom view of the external closures shown in Figs. 4, 5, 6, 7 and 8 omitting the cross bar. Figs. 75 5, 6, 8 and 9, the suspensory and electrical attachments are omitted. Fig. 10 is a plan of the device looking down at the top thereof.

It is to be understood that each of the three forms shown are substantially circular in all 80 cross sections.

Referring first to the form illustrated in Figs. 1, 2, and 3, the supporter consists of a substantially pear-shaped body portion 1, a contracted neck 2 and a head 3. The body 85 portion 1 is preferably round in cross section and enlarges abruptly from the neck so as to form a shoulder or face 4, and a swell or enlargement 5, said body portion tapering above said swell to form a contracted or 90 somewhat pointed end 6.

The neck 2 is desirably cylindrical, and the head 3 has a flat upper face 7 acting as a shoulder. The supporter is hollow throughout, having a perforation, bore or passage 8 95 extending longitudinally through the same from end to end. To the lower end of the supporter may be secured an attaching means, such as a cross bar 9 with eyes 10 adapted for engagement with hooks 11 of 100 suspensory tapes 12, shown in part in Fig.

1. An electrical conductor 13 has a terminal hook 14 also adapted to engage in one of said eyes, as shown in said figure. The outer face of the end or button 3 is curved sufficiently to afford space between the perforated ends of the bar 9 and the surface to permit of the insertion of the ends of the tape 12, and also the insertion of the hook 14.

I have found that zinc is the most desirable 110 material for the supporter, and I therefore prefer to form the same of an integral piece

of zinc, smoothly finished, with the attaching device soldered thereto.

In using the supporter, it is inserted point end upwards, into the rectum until the swell 5 passes the sphincter ani, which thereupon closes upon the contracted neck 2 and engages above and below with the faces 4, 7, to hold the supporter from displacement in either direction. If the hemorrhoids are 10 protruding, they will be pushed back into the rectal passage by this operation, and in any case, the pressure, distending and separating effect of the supporter will afford relief. The zinc surface, in contact with the 15 congested membrane, has a specific stimulative and curative effect. To further increase the stimulative and curative effect the conductor 13 may be attached, said conductor leading to any suitable source of current, 20 such as an electric belt, to conduct an electric current into the parts affected. The suspensory devices 11 are attached in any suitable way to the person in well-known manner. The bore or passage 8 through the 25 supporter provides for the free passage of gas from the bowels, and by forming the inner end with a long, slender taper ending substantially in a feather edge, the intestines fit closely around it and above the end they 30 come into contact, and thereby prevent the passage of any of the contents except the air which escapes through the perforation through the plug or supporter.

Referring now to the form shown in Figs. 35 4 and 5, the pear-shaped inner end or body portion 1" which constitutes the inner closure, is provided with a more abrupt base 4' than the base 4, in Figs. 1 and 2, to receive the support of the sphincter recti. Said body 40 tapers from said base in substantially the same form as in Figs. 1 and 2; that is to say, said body tapers from the base in the form of a spindle generated by the revolution of a curved line around an axis exterior to said 45 curve, said axis being the straight perforation, bore or passage 8. The outer closure or button-like outer end or head 3' of this form, has a convexity 15 at the neck 2' and bead 16, a channel 17 being provided between 50 the bead and neck, said channel extending around the neck at a distance therefrom. By this construction the outer closure is adapted to return and retain the walls of the rectum which may ordinarily be subject to 55 protrusion.

In Figs. 7 and 8, the inner closure is pro-

vided with a more abrupt shoulder or base 4² than that shown in either of the other views. This form is especially adapted for cases in which the sphincter recti is weakened or relaxed. 60

The curved form of the spindle shown in the several views is especially adapted to sustain the varicocele veins or hemorrhoids, and to perform the massaging action. 65

It will be understood from the plan view 10 that the body 1, 1", 1"" in the several views, is preferably circular in cross section throughout, and devoid of any ridges or corrugations which may tend to form folds in 70 the inner coating of the rectum. The tendency of the inclosure being to smooth and keep straight and true the lower part of the rectal lining.

It is to be understood that the suspensory 75 device shown to a considerable extent in Fig. 1, is applicable to all the forms.

What I claim is:—

1. A rectal supporter comprising a longitudinally-perforated zinc body having a pear 80 shaped inner end, a neck, and a substantially button-shaped outer end, a perforated cross-bar on the button, the outer surface of said button being rounded to form a space between the ends of the bar and said surface, 85 tapes secured to the ends of said bar, and a conductor hooked in one of the perforations in the ends of the bar.

2. A rectal supporter comprising a spindle-shaped body having a distended portion terminating on one end in a slender tapering contraction and at the other abruptly in a neck, said neck having a head formed in continuation therewith and consisting of a disk-like button-shaped trough arranged to snugly 95 fit the anal end, and an opening extending centrally through the supporter from end to end. 90

3. A rectal supporter comprising a longitudinally-perforated zinc body consisting of 100 a spindle-shaped inner end, a neck and a button-like outer end, said inner end having a long, slender taper ending substantially in a feather edge, and said ends forming shoulders at the ends of the neck. 105

In testimony whereof, I have hereunto set my hand at Los Angeles California this 2d day of October 1905.

HERBERT E. CUNNINGHAM.

In presence of—

JAMES R. TOWNSEND,

JULIA TOWNSEND.
